H. GRAY

COCK

Filed July 24, 1923

Harry Gray INVENTOR.

BY Jesse R Stone

ATTORNEYS.

Fig. 4

UNITED STATES PATENT OFFICE.

HARRY GRAY, OF HOUSTON, TEXAS.

COCK.

Application filed July 24, 1923. Serial No. 653,448.

To all whom it may concern:

Be it known that I, HARRY GRAY, a citizen of the United States, residing at Houston, Harris County, Texas, have invented a certain new and useful Improvement in Cocks, of which the following is a full, clear, and exact description, such as will enable others skilled in the art to which it appertains to make and use the same.

10 My invention relates to cocks and has particular application to the valve cocks employed in the dispensing of liquids.

It is an object of my invention to provide a cock which may be easily and cheaply 15 manufactured, so that it may be made in quantities and, if desired, may be used but a few times and then thrown away.

Another object is to provide a packing for the valve which will be effective to prevent 20 leakage and yet simple in construction. It is also desired to so mount the packing as to prevent its rotation with the valve plug.

Another object is to provide an effective 25 means of retaining the valve plug in operative position.

Referring to the drawing herewith wherein like numerals of reference are applied to like parts in all the views; Fig. 1 is a top plan view of the invention. Fig. 2, a side 30 elevation, certain parts being broken away in central longitudinal section. Fig. 3 is a transverse section on the plane 3—3 of Fig. 2. Fig. 4 is a bottom view. Fig. 5 is a section taken on the plane 5—5 of Fig. 6. Fig. 6 is a central longitudinal section of 35 the valve housing of a slightly different embodiment showing the valve plug in elevation. Fig. 7 is a transverse section on the plane 7—7 of Fig. 6.

40 My invention has particular application to cocks or spigots which are employed on barrels or other large containers of liquids for shipment. In such cases the cock is used to discharge the contents of the container 45 as said contents are used, but when the container is empty, it is contemplated that the cock may, if desired, be thrown away or destroyed. My invention is not limited entirely for this use, however, as it is obvious 50 that it may have a wide application in various situations.

In the embodiment disclosed in Figs. 1 to 4, inclusive, there is a tubular open ended casing 8, the main body of which is shown 55 as cylindrical, the attaching end is reduced slightly in diameter at 9 both externally and

internally and again at 10 where it is threaded for screwing within an opening or bung of a container to be emptied.

Internally there is a central chamber 11 having a lateral opening 12 to provide an outlet, shown in the drawing as formed without a nozzle. As seen in Fig. 3, the chamber 11 has its walls recessed somewhat on one side at 15 opposite the opening 12, to provide a seat for a flat strip of packing material 13. At each longitudinal side of the recessed portion 15 the recess terminates in a shoulder 14 against which the packing strip contacts. This serves to hold the packing in position preventing rotative movement thereof as the valve is moved.

At the outer end of the casing 8, the interior diameter is slightly increased to seat a packing ring 16. At the inner end of the 75 chamber within the reduced portion 9, is a seat for a packing ring 17, which is smaller in diameter than is the chamber 11.

A valve plug 18 fits within the casing and its lining of packing and its open inner end 19 has a bearing within the packing ring 17. The outer closed end 20 of the plug extends outside the casing and has an operating handle 22 thereon. A radially extending flange or shoulder 23 on the plug rests 85 against the outer packing ring 16.

The intermediate portion of the plug within the chamber has its walls thickened externally on one side at 24, the opposite side 25 being comparatively thin. The thickened 90 wall has an outlet opening 26 therein which is adapted to be rotated into registration with the opening 12 in the casing.

The valve plug is retained in position in the casing by lugs 29 projecting from the 95 outer end longitudinally of the casing. There are at least two of these lugs 29, as seen in Fig. 1. They are made of soft metal and when the plug is in position said lugs are bent inwardly to fit snugly against the 100 rounded outer end of the plug, allowing it to rotate but preventing it from movement longitudinally.

In the operation of the invention the device is assembled as disclosed in the drawing, and is secured within the barrel or other container holding liquid which is to be dispensed. The valve is closed by turning the valve plug so that the thickened eccentric side thereof having the opening 26 therein is 110 held tightly against the packing strip 13. This will prevent leakage through the open-

ing 26 therein. On the side of the plug toward the opening 12 in the casing, the chamber is not packed, but there is the lower packing ring 17 and the upper packing ring 16 which close the space about the plug above and below the opening so that no leakage may occur. When the plug is forced within its seat in the casing, the shoulder 23 bearing against the packing ring 16 will 10 serve to compress and expand said ring, and a lower shoulder 30 on the plug also acts to compress the packing ring 17. When it is desired to empty a portion of the contents from the container the plug is turned so 15 that the opening 26 registers with the opening 12 in the casing, and thus allows the liquid to escape. It is contemplated that the openings 26 and 12 will be of approximately the same area and may, if desired, 20 be made of the same area as is the interior diameter of the casing at 10. This allows the full volume of liquid which may find outlet through the valve casing, to flow unimpeded through the outlet of the valve.

25 In the embodiment shown in Figs. 5, 6 and 7, the main features of the valve are the same as in the embodiment just described. As shown in the drawing, however, the packing ring 17' is somewhat narrower in 30 width and projects inwardly from the lower end of the chamber 11' so that the lower end of the plug 18' will contact therewith. At the outer end of the casing the packing ring 16' may also be made somewhat narrower 35 than in the previous embodiment, thus providing a cock somewhat shorter in length than in the previous embodiment.

The means by which the valve plug is maintained in its operative position in this 40 embodiment is materially different than that disclosed in the first embodiment. The outer end of the valve casing is slightly enlarged in diameter and is undercut at 31 to provide a groove. This groove has its upper wall inclined upwardly from one side to the other, as shown at 32, thus providing an inclined plane against which the plug may 45 operate, as will be presently described.

The plug 18' is formed on its outer end 50 with a laterally extending resilient flange 33. This flange has an upper extension 34 separated from the inner portion by a slot 35, one of these extensions being formed on each side of the plug as shown in Fig. 5. 55 The extension projects about half way around the plug, and has at its end an outwardly projecting portion 36 having a forward shoulder 37 thereon. The groove 31 in which the flange projects has at diametrical 60 opposite points inwardly extending bosses 38 to limit the movement of the resilient flange or extension, 34. As the valve in this embodiment is made of resilient material, it is necessary, in inserting the 65 plug within the casing, to spring the lugs

36 at the ends of the resilient member 34 inwardly, so as to get it by the constricted opening 39 in the end of the casing. When it is then released it will by its own resiliency spring outwardly to fit within the 70 groove 31 and may then be rotated. Due to the fact that the wall 32 of the groove 31 is inclined, the rotation of the valve will act as a screw to throw the plug resiliently downward so as to compress the packing 75 rings 16' and 17', and thus hold them in expanded position so as to maintain the valve fluid tight. The handle 22' in this embodiment is spaced outwardly away from the body of the plug by means of a neck or 80 handle, 40.

In the operation of this embodiment of my invention, the parts are assembled as shown, and when the plug is inserted within the casing the resilient member 34 is compressed 85 inwardly so as to force it through the opening 39, and it is then in position to be rotated; and when rotated so that the eccentric portion 24 is held against the packing strip 13, the resilient extension 34 will also act 90 as a screw, forcing the plug inwardly so as to compress the packing rings 16' and 17', making the joint absolutely tight. When it is desired to open the valve the plug will be rotated so as to bring the opening 26 into 95 registration with the opening 12, and in so rotating the plug the shoulder 37 will contact with the shoulder of the boss 28 when the openings are exactly registering. The packing will be somewhat released from 100 compression, but no leakage will occur, due to the fact that the fluid finds a ready opening through the outlet in the valve.

In the construction of these two embodiments of my invention, it is contemplated 105 that the different parts may be made quickly and cheaply, so that, if desired, the valve may be thrown away when the container has been entirely emptied. This can be best accomplished in the embodiment shown in 110 Figs. 1 to 4, wherein the working parts may all be made of soft metal and may be die cast or otherwise cheaply formed. The manner in which the valve is packed to prevent leakage will be entirely effective, even though the valve may be repeatedly used before it is discarded. The securing of the valve plug in position within the casing by means of the lugs 29 provides a retaining 115 means which may be very readily manipulated, and in a temporary valve of this kind, 120 will be entirely effective.

In the embodiment shown in Figs. 5 to 7 inclusive, the material may best be of some 125 resilient metal, so that the best action of the retaining means 34 may be accomplished. This valve has the advantage, however, that the retaining means not only prevents the removal of the plug from the casing, but also serves to compress the packing rings 130

so that when the valve is closed the leakage about the plug is absolutely prevented. The further objects and advantages of my invention will be apparent to one skilled in the art, without further description.

What I claim as new and desire to protect by Letters Patent is:

1. In a cock, a tubular casing one end of which is threaded for attachment within a container, a central chamber having an outlet opening on one side thereof, the opposite side being recessed, packing in said recessed portion, a hollow valve plug in said chamber having its wall thickened on one side whereby it is made eccentric within said chamber, there being an outlet opening in said thickened wall, packing between said plug and said casing above and below said eccentric portion and means to retain said valve plug removably in said casing.
2. In a cock, a tubular casing one end of which is threaded for attachment within a container, said casing having a lateral outlet opening, a central chamber having its walls recessed part way round to receive a strip of packing material, packing rings above and below said chamber, a valve plug in said casing having its walls thickened on one side within said chamber whereby it fits eccentrically therein, said thickened wall having an opening therein adapted to register with the outlet in said casing, and means to retain said plug in said casing.
3. In a cock, an open ended tubular casing having a lateral outlet opening therein, packing rings in said casing adjacent the upper and lower ends thereof, a chamber between said rings having its walls recessed but part way round the same, a strip of packing in said recess, a hollow valve plug in said casing having its walls thickened on one side within said chamber, whereby it fits eccentrically in said chamber, there

being an opening in said plug through the thickened wall, means to rotate said plug 45 and means to retain said plug in position in said casing.

4. In a cock, an open ended casing having a lateral outlet in one side thereof, packing rings in said casing adjacent the upper and lower ends thereof, a chamber between said rings, a strip of packing material extending part way around said chamber opposite said opening and held against rotation therein, a valve plug having its outer end closed fitting axially within said casing the outer face of said plug within said chamber being eccentric and having an opening therein, and means to rotate said plug.

5. In a cock, a tubular casing having a lateral outlet, a valve plug extending longitudinally through said casing having an opening adapted to register with said outlet when said plug is rotated, packing means 65 in said casing, and means to retain said plug removably in said casing comprising soft metal lugs on said casing bent around the said plug and fitting closely against the closed outer end thereof, and adapted to 70 be bent back when said plug is removed.

6. In a cock, a tubular casing having an axial inlet and a lateral outlet, a hollow plug closed at one end and rotatable in said casing with an opening therein adapted to 75 register with said outlet when said plug is rotated into open position, a packing strip on the interior side of said casing opposite said opening and an eccentric face on said plug adapted to fit closely against said strip 80 only when said valve is closed.

In testimony whereof, I hereunto affix my signature, this the 20th day of July, A. D. 1923.

HARRY GRAY.
